UNITED STATES PATENT OFFICE

122,031

DESIGN FOR A NECKLACE

Maximilian C. Meyer, Brooklyn, N. Y.

Application April 24, 1940, Serial No. 91,897

Term of patent 3½ years

To all whom it may concern:

Be it known that I, Maximilian C. Meyer, a citizen of the United States, residing at Brooklyn, in the county of Kings and State of New York, have invented a new, original, and ornamental Design for a Necklace, of which the following is a specification, reference being had to the accompanying drawing, forming a part thereof.

The figure is a perspective view of a necklace showing my new design.

I claim:

The ornamental design for a necklace, as shown.

MAXIMILIAN C. MEYER.
